US0D1108016S

(12) **United States Design Patent** (10) **Patent No.:** **US D1,108,016 S**
(45) **Date of Patent:** **** Dec. 30, 2025**

(54) **RAZOR**

(71) Applicant: **KAI R&D CENTER CO., LTD.**, Seki (JP)

(72) Inventors: **Hiroshi Yamakose**, Seki (JP); **Mai Kadokura**, Seki (JP); **Shunsuke Shioya**, Seki (JP); **Toshiki Takagi**, Seki (JP)

(73) Assignee: **KAI R&D Center Co., Ltd.**, Seki (JP)

(**) Term: **15 Years**

(21) Appl. No.: **29/911,400**

(22) Filed: **Sep. 1, 2023**

Related U.S. Application Data

(63) Continuation of application No. 17/773,300, filed as application No. PCT/JP2020/041257 on Nov. 4, 2020.
